UNITED STATES PATENT OFFICE.

KENNETH M. SCOVILLE, OF MILWAUKEE, WISCONSIN.

DESIGN FOR A BUTTON.

54,690.

Specification for Design.

Patented Mar. 9, 1920.

Application filed June 27, 1919. Serial No. 307,219. Term of patent 3½ years.

To all whom it may concern:

Be it known that I, KENNETH M. SCOVILLE, a citizen of the United States, and a resident of Milwaukee, county of Milwaukee, and State of Wisconsin, have invented a new, original, and ornamental Design for Buttons, of which the following is a specification, reference being had to the accompanying drawing, forming a part thereof.

Figure 1 is a front elevation of a button embodying the new design, and Fig. 2 is a side elevation thereof.

I claim:

The ornamental design for a button as shown.

In witness whereof I have hereunto subscribed my name.

KENNETH M. SCOVILLE.
